(57) **CLAIM**

The ornamental design for a motorized bicycle frame, as shown and described.

DESCRIPTION

FIG. 1 is a right side elevation view of a motorized bicycle frame as installed within a complete motorized bicycle assembly;

FIG. 2 is a front and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a bottom plan view thereof; and,

FIG. 8 is a top plan view thereof.

The broken lines in the drawings illustrate the portions of the motorized bicycle frame, which form no part of the claimed design.
